UNITED STATES PATENT OFFICE.

ALPHONSE JOSEPH LAVOIE, OF MONTREAL, QUEBEC, CANADA.

CHUCK.

Application filed December 27, 1919. Serial No. 347,835.

To all whom it may concern:

Be it known that I, ALPHONSE JOSEPH LAVOIE, a subject of the King of Great Britain, and residing at 294 Wilson Avenue, in the city and district of Montreal, in the Province of Quebec, in the Dominion of Canada, have invented a new and useful Chuck, of which the following is the specification:

10 The invention relates to chucks as described in the present specification and illustrated in the accompanying drawings that form part of the same.

15 The invention consists essentially of the novel means employed for adjusting the jaws to the particular work and for engaging the work when finally adjusted, whereby a considerable range is insured in the use of chucks pneumatically operated, and the work gripped with great facility and firmness and readily released.

20 The objects of the invention are to devise in machinery a work holder that will be economical to use in the matter of saving time and labour in adjusting and gripping operations; to eliminate slipping during the turning of any piece, and facilitate the centering of said piece; to simplify the parts in lathe attachments; and generally to provide 25 a comparatively cheap, durable and efficient chuck.

30 In the drawings, Figure 1 is a longitudinal sectional view of the chuck showing both a jaw adjusting member and a gripping member as well as the general arrangement 35 of the pneumatic means for operating.

Figure 2 is a plan view of the jaw head and jaws.

40 Figure 3 is a perspective detail showing the engagement of the wedging dog with the jaw part.

Figure 4 is a perspective detail of the wedging dog.

45 Figure 5 is a perspective detail of the jaw part coacting with the dog.

Figure 6 is a perspective detail of the screw plug in the adjusting mechanism.

50 Figure 7 is a perspective detail of the piston head.

Figure 8 is a longitudinal sectional view showing a plain form of piston, while the other parts remain identical with the corresponding parts of the other figures.

55 Figure 9 is a sectional detail showing the jaw recesses and locking grooves.

Figure 10 is a detail showing the inner side of the body.

Like numerals of reference indicate corresponding parts in each figure.

Referring to the drawings, 1 is the body 60 of the machine, which is recessed in the inner side 2 to form the rim 3, further recesses 4 being made in the bottom of the inner recess 2 to form spring chambers, and containing the bosses 5 as posts for the piston springs. 65

Between the recesses 4, the radial jaw recesses 6 are made from the outer side and adjoining the jaw recesses the slots 7 are formed for the wedge dogs as explained 70 hereinafter.

The jaws 8 are preferably formed with three gripping faces 9, 10, and 11, and are slidably arranged in the jaw recesses 6 preferably with the tongue and groove fastenings 12, said jaws having on the inner side the threaded recess 13. In the enlarged inner ends of the jaw recesses 6, the base blocks 14 of the jaws are slidably arranged. These blocks are formed with the plain 80 curved, longitudinal groove 15 terminating at 16, adjacent to the outer end, the block beyond said groove forming a stop for the adjusting screws. At the inner end of the groove 15, the said groove is closed in to 85 form a plug hole 17. On a side face of each base block 14 the bar teeth 18 are formed and extend in an inclined direction there-across and are in line with the dog slots 7.

The dogs 19 have similar bar teeth, though 90 fewer in number, and these teeth slide between the bar teeth 18, and as the dog teeth 20 are also inclined, the engagement of the dogs with the blocks will produce a wedging effect and drive the blocks inwardly. 95

The dogs 19 at their inner ends are formed with the flange 21, which engages in the sockets 22 each of said sockets being formed by an angle piece 22^a and a straight parallel piece 22^b on the face of the piston 23. The 100 posts 24 also extend from the piston between the sockets 22 and are in alignment with the posts 5. The springs 25 encircle the posts 5 and the posts 24, and normally keep the piston to its inward position, that is to say, 105 the said springs normally keep the jaws from engagement.

The piston 23 is introduced into the inner recess 2, the latter forming the cylinder of the machine. The cylinder is closed by the 110

head 26 and a face plate 27 covers the head 26, both being secured to the rim 3 by the screws 28. The face plate 27 has a central threaded spindle orifice 29, into which the 5 hollow spindle 30 is screwed, and the head 26 is shown in Figure 1 with a central threaded orifice 31, into which is inserted an extension cup 32 having the air orifice 33 at the end thereof connected to the feed pipe 34.

10 The inner extension cup 35 is screw-threaded into the piston 23 and is slidably arranged in the body 1 in alignment with the work hole 36. The cup 35 or like member forms a dust shield guarding the 15 various parts of the device and also forms a guide and work recess.

The cover plates 38 close in the dog slots 7.

In Figure 8 the only difference is that 20 there are no extension cups to receive the end of the work as the piston 39 is perfectly plain and the head 40 has the central inlet 41 into which the air pipe 42 is screwed, otherwise the construction is the same as already described.

25 In the screw plug holes 17, screw plugs 43 or bushings form bearings for the adjusting screws 44, the latter having the circular reduced heads 45 turning in said bushings and formed with the squared driving 30 holes 46.

The outer ends 47 of the screws abut the 35 stops 16 and said screws engage the inner threaded recesses 13 of the jaws 8, consequently by inserting a driving tool in the driving holes 46, the jaws are manually 40 adjusted to their inner or outer positions to grip or to release the work, and the final grip is made pneumatically through the dogs 19.

45 In order to more effectually explain the invention, the operation will now be described briefly. The body, through its connection with the face plate, is mounted on the spindle of the lathe and the work is inserted between several jaws, that is to say, either one 50 of the step jaws. These jaws are brought up to the work by operating the adjusting screws 44, as the actual jaws move independently of the base blocks in the manual operation.

The next step is to turn on the air, and this has the effect of sending the piston forwardly and consequently the dogs 19. The dogs 19, through their teeth 20, wedge at the

base blocks 14 through their teeth 18, and as 55 the base blocks and jaws are intimately associated and outside of the manual adjustment travel coincidentally, the said jaws 8 are firmly and quickly brought to the work and held there so long as the air pressure is maintained, but immediately that the air is exhausted, the jaws automatically release themselves from the work, for the springs 25 return the piston to its original non-acting position in the cylinder and in 60 consequence, of course, the dogs are brought back, which produces the automatic disengagement from the work.

Various changes may be made in the details of the construction without departing 70 from the spirit of the invention, and so long as these changes are within the scope of the claims for novelty following, the protection accorded shall not be invalidated.

75 What I claim is:—

1. A chuck comprising a body and a plurality of radially movable jaws, jaw bases 80 slideable in said body in combination with a reciprocating member carrying jaw operating dogs having an inclined engagement with said jaw bases, said dogs having a radial slip-in engagement with said reciprocating member and a longitudinal sliding engagement with the chuck body guiding and maintaining the line of movement of said 85 dogs parallel with the axis of said chuck.

2. In a chuck, a body having an inner recess forming a cylindrical chamber and spring recesses in the bed of said chamber and radial jaw slots inwardly from the outer 90 face, a head closing said cylinder and having a cup extension screw-threaded thereinto, and an air inlet into said cup extension, an air feed pipe connected to said inlet, a face plate rigidly secured to said body 95 through said head and having a suitable mounting orifice, a piston operating in said cylinder and carrying centrally a cup extension operating in the aforesaid cup extension and sliding in said body opposite the work hole, wedging dogs secured to said piston and jaws having wedging faces coacting with said dogs and slidably arranged in said radial slots.

Signed at the city of Montreal, Quebec, 105 Canada, this 9th day of December, 1919.

ALPHONSE JOSEPH LAVOIE.
